UNITED STATES PATENT OFFICE

121,373

DESIGN FOR A BROOCH PIN OR SIMILAR ARTICLE

Victor Primavera, Providence, R. I.

Application May 11, 1940, Serial No. 92,305

Term of patent 3½ years

To all whom it may concern:

Be it known that I, Victor Primavera, a citizen of Italy, residing at Providence, county of Providence, State of Rhode Island, have invented a new, original, and ornamental Design for a Brooch Pin or Similar Article, of which the following is a specification, reference being had to the accompanying drawing, forming a part thereof.

Fig. 1 is a top plan view showing my new design for a brooch pin or similar article; and

Fig. 2 is an edge elevation thereof.

The dominant part of the design is shown in full lines.

I claim:

The ornamental design for a brooch pin or similar article, substantially as shown and described.

VICTOR PRIMAVERA.
